TRAY ATTACHMENT FOR A GOLF CART

Mildred G. Zimmers, Chicago, Ill., assignor to Parway
Mfg. Co., Inc., Chicago, Ill., a corporation of Illinois

Filed Jan. 2, 1963, Ser. No. 73,027

Term of patent 14 years

(Cl. D34—5)

FIG. 1 is a top plan view of a tray attachment for a golf cart showing my new design.

FIG. 2 is a bottom plan view of the article of FIG. 1.

FIG. 3 is a front elevational view of the article taken in the direction of the arrows 3-3 shown in FIG. 1.

FIG. 4 is a rear elevational view of the article taken in the direction of the arrows 4-4 shown in FIG. 1 rotated 180 degrees.

FIG. 5 is a side elevational view of the article as it appears when viewed in the direction of the arrows 5-5 shown in FIG. 3.

FIG. 6 is a side elevational view of the article as it appears when viewed in the direction of the arrows 6-6 shown in FIG. 3.

I claim:

The ornamental design for a tray attachment for a golf cart, as shown.
